(57) **CLAIM**

I claim the ornamental design for morcellator motor drive, as shown and described in the drawings.

DESCRIPTION

FIG. 1 is a side perspective view of a morcellator motor drive in accordance with the new design;

FIG. 2 is a front view of the morcellator motor drive of FIG. 1;

FIG. 3 is a side perspective view of the morcellator motor drive of FIG. 1, shown with morcellator;

FIG. 4 is a side perspective view of the morcellator motor drive of FIG. 1, shown in use; and,

FIG. 5 is a perspective view of the morellator motor drive of FIG. 1 shown in use.

The broken lines showing are for illustrative purposes and form no part of the claimed design.

1 Claim, 3 Drawing Sheets

FIG. 4

FIG. 5
